Attorney,

UNITED STATES PATENT OFFICE.

EDGAR M. TYLER, OF DETROIT, MICHIGAN, ASSIGNOR OF ONE-HALF TO RICHARD J. WELSH, OF KALAMAZOO, MICHIGAN.

PORTABLE ELECTRIC LAMP.

1,007,404.

Specification of Letters Patent. Patented Oct. 31, 1911.

Application filed June 5, 1911. Serial No. 631,258.

To all whom it may concern:

Be it known that I, EDGAR M. TYLER, a citizen of the United States, residing at Detroit, Michigan, have invented certain new and useful Improvements in Portable Electric Lamps, of which the following is a specification.

This invention relates to improvements in portable electric lamps.

10 The main objects of this invention are: First, to provide an improved portable lamp particularly adapted for the use of travelers, which is compact when collapsed or arranged for carrying, and the breakable parts 15 effectively protected. Second, to provide an improved portable lamp embodying these features which is quickly adjusted for use as a stand lamp, or as a suspended lamp.

Further objects relating to economies and 20 structural details and to details of operation will definitely appear from the detailed description to follow.

I accomplish the objects of my invention by the devices and means described in the 25 following specification.

The invention is clearly defined and pointed out in the claims.

A structure which is a preferred embodiment of my invention is clearly illustrated in 30 the accompanying drawing, forming a part of this specification, in which:

Figure I is a perspective view of a structure embodying the features of my invention, portions of the casing 1 being broken 35 away to show the arrangement of the parts therein when the structure is adjusted or arranged for transportation. Fig. II is a perspective view of the lamp adjusted as a stand lamp. Fig. III is a detail side elevation, partially in vertical section, of the cap 40 and reflector. Fig. IV is a detail perspective view of the coupling part of the reflector.

In the drawing similar reference characters refer to similar parts throughout the 45 several views.

Referring to the drawing, the lamp base 1 is in the form of a casing adapted to serve as a container or receptacle for the lamp, the lamp cord and shade. The cap 2 of the 50 casing 1 is adapted to telescope therein and is reversible, being provided with a stud 3 and the casing being provided with a bayonet slot 4 to engage said stud, so that the top may be reversed to hold the lamp in an op-

erative position, as shown in Fig. II, or suspended in the casing, as shown in Fig. I.

The lamp socket 5 is mounted on the cap 2 by means of the screws 5'. The opposite side of the cap is preferably provided with a suspending hook 6, which is pivoted at 7, so 60 that it may be folded down into the recess 8 provided therefor in the cap. By means of this hook, the cap 2 may be suspended as from the head of a bed or any suitable support.

65 The connecting cord 9 is connected to the socket 5 of the lamp in the side of the socket, as at 11, so that the cord can be arranged in the casing and the cap replaced. The connecting plug 12 is of any suitable type.

70 The reflector 13 is adapted to be removably engaged with the cap 2, and the reflector being of elastic metal, its lower edge 14 is adapted to be engaged within the rim of the cap. The reflector is thus supported so 75 that it can be readily assembled or placed as circumstances may dictate.

A suitable reflector might be carried by 80 the socket. Such means of supporting the reflector being very common, I do not illustrate it as my invention does not pertain to that means.

The bottom of the casing 1 is provided with a weight 15 (see Fig. I) to give the 85 lamp stability. By arranging the hook 6 to fold down into the depression or recess 8 in the cap, the cap may also be used as a base, if desired.

90 My improved lamp is especially designed by me for the use of travelers, and when arranged as shown in Fig. I, for transportation or storage, is very compact, and the lamp is supported so that it is not likely to be injured. The lamp is very quickly adjusted for use, and is adapted to be assembled for use in various relations—that is, as shown in Fig. II, or the cap 2 may be used as a base, the reflector adjusted or removed as desired, or the lamp suspended by means of the hook. The structure further has the 100 advantage of being very economical to produce.

I have illustrated and described my improvements in detail in a simple embodiment. I am aware, however, that considerable variation in structural details is possible without departing from my invention, but as these variations will no doubt be

understood by those skilled in the art to which this invention relates, I have not attempted to illustrate or describe the same herein.

5 Having thus described my invention, what I claim as new and desire to secure by Letters Patent is:

1. In a portable lamp, the combination of a casing adapted to serve as a base; a cap having a flange adapted to fit into said casing; a lamp socket mounted on one side of said cap, said cap being provided with a securing member whereby it may be reversed in said

10 casing to support the lamp in operative position, or to suspend the same within the casing; a suspending hook on the other side of said cap, said cap having a recess into which the hook is adapted to collapse whereby the cap may be used as a base for the 15 lamp or suspended by said hook; a connecting cord and plug, said cord being connected to the side of the lamp socket, said casing being adapted to receive said cord and plug when the lamp is reversed therein; and a 20 reflector conformed to the lamp and having a 25 engaging portion adapted to engage in the said cap flange whereby the reflector is removably and adjustably supported therein.

2. In a portable lamp, the combination of 30 a casing adapted to serve as a base; a cap having a flange adapted to fit into said casing; a lamp socket mounted on said cap, said cap being provided with a suitable joint whereby it may be reversed in said 35 casing to support the lamp in operative position, or to suspend the same within the casing; a connecting cord and plug, said cord being connected to the side of the lamp 40 socket, said casing being adapted to receive said cord and plug when the lamp is reversed therein; and a reflector having an 45 engaging portion adapted to engage in the said cap flange whereby the reflector is removably and adjustably supported therein.

45 3. In a portable lamp, the combination of a casing adapted to serve as a base; a cap having a flange adapted to fit into said casing; a lamp socket mounted on one side of said cap, said cap being provided with a

securing member whereby it may be reversed in said casing to support the lamp in operative position, or to suspend the same within the casing; a suspending hook on the other side of said cap, said cap having a recess into which the hook is adapted to collapse whereby the cap may be used as a base for the lamp or suspended by said hook; and a connecting cord and plug, said cord being connected to the side of the lamp socket, said casing being adapted to receive said cord and plug when the lamp is reversed therein.

4. In a portable lamp, the combination of a casing adapted to serve as a base; a cap having a flange adapted to fit into said casing; a lamp socket mounted on said cap, said cap being provided with a suitable joint whereby it may be reversed in said casing to support the lamp in operative position, or to suspend the same within the casing; and a connecting cord and plug, said cord being connected to the side of the lamp socket, said casing being adapted to receive said cord and plug when the lamp is reversed therein.

5. In a portable lamp, the combination of a casing adapted to serve as a base; a reversible cap for said casing; a lamp socket mounted on one side of said cap; a suspending hook on the other side of said cap; and a connecting cord connected to said 75 socket.

6. In a portable lamp, the combination of a casing adapted to serve as a base; a reversible cap for said casing; a lamp socket 85 mounted on said cap whereby a lamp arranged in said socket may be supported in an upright position on said base or suspended therein; and a connecting cord connected to said socket.

In witness whereof, I have hereunto set my hand and seal in the presence of two witnesses.

EDGAR M. TYLER. [L. S.]
